UNITED STATES PATENT OFFICE.

DONALD BARNS MORISON, OF HARTLEPOOL, ENGLAND.

STAMPING APPARATUS FOR CRUSHING ORES, &c.

SPECIFICATION forming part of Letters Patent No. 755,686, dated March 29, 1904.

Application filed July 6, 1900. Serial No. 22,695. (No model.)

To all whom it may concern:

Be it known that I, DONALD BARNS MORISON, a subject of the Queen of Great Britain and Ireland, residing at Hartlepool, in the county of Durham, England, have invented Improvements in Stamping Apparatus Suitable for Crushing Ores and for other Purposes, of which the following is a specification.

This invention has reference to stamping apparatus (such as mills for crushing ores and other substances, stamp-hammers, and like apparatus) of the kind in which the stamp-heads are lifted by means of the rising movement of positively-driven parts communicated to the stamp-heads through the medium of bodies of liquid, as described in the specification of former Letters Patent, No. 591,560, granted to me. The liquid in such a stamping apparatus is contained within cylinders beneath pistons connected to the stamp-heads, each cylinder being suspended from one of the cranks of a crank-shaft and being formed with a reservoir for the liquid, some of which is caused by the relative movements of cylinder and piston to flow from the cylinder to the reservoir at a gradually-increasing velocity through a port of decreasing area during the lifting-stroke, so as to cushion the lift of the stamp. In such arrangements the work done in thus forcing the liquid through the port for the purpose of cushioning is lost.

Now an object of this invention is to obviate this loss as far as possible, for which purpose a hydropneumatic cushioning arrangement is adopted. The elastic compressive resistance of air combined with a gradually-increasing passive resistance created by forcing water at an increasing velocity through a port of gradually-decreasing area is employed in such a manner that as the upward acceleration of the piston and stamp, due to the motion of the cylinder, diminishes the air re-expands and raises the piston and stamp relatively to the cylinder through a distance corresponding to the compression and that the height of the lift due to re-expansion of the air will not be great enough to interfere with the attainment under the action of gravity of the required number of drops per minute as

would be the case if air alone were used as the cushioning medium.

My invention also has reference to other improvements hereinafter described, and set forth in the claims.

The accompanying drawings illustrate, by way of example, a five-stamp battery for crushing ores with my improvements embodied therein, Figure 1 being a front elevation and Fig. 2 a sectional end view of the battery. Fig. 3 is a plan, to an enlarged scale, of one of the positively-driven cylinders with the cover removed. Figs. 4 and 5 are vertical sections taken, respectively, on the lines A A and B B of Fig. 3. Fig. 6 is a horizontal section on the line C C, Fig. 4; and Figs. 7 to 13 are detail views hereinafter referred to.

a are the lifting-cylinders, similar to those used in my previous specification, each of which is formed with sleeves *b*, working on guide-rods *c*, and has bolted to it a cover *d*, formed with lugs *e*, to which a gudgeon-pin *f* connects the bottom end of a connecting-rod whose upper end is attached to one of the cranks of the driving-shaft *g*.

h is the chamber or reservoir for liquid and surrounds the cylinder *a* and communicating freely with the upper part thereof and with the lower part thereof through a port *i*. There may be several ports at or about the same level instead of a single port *i*, as shown. 80

j is the piston, connected to the stamp-head *k*.

In communication with the cylinder *a* there is in the present arrangement an air vessel *l*, the port *m* leading to which is preferably below the port *i*. When a stamp-shoe *k'* is resting upon the die *o* and its cylinder *a* is at the bottom of its stroke, the port *i* is open and the lower portion of the cylinder is filled with liquid. When the cylinder ascends, the water displaced by the relative motion of the cylinder and piston is forced partly through the port *i* and partly into the vessel *l*, the air in which reduces shock. The effective area of the port *i* will be gradually decreased by the piston, the pressure beneath which will gradually increase until it becomes sufficient to raise the stamp, at which time the velocity of the cylinder will be moderate. Ordinarily

the piston will close the port *i* just before the stamp is raised. The cylinder, carrying the stamp with it, continues to ascend at a velocity which increases up to about mid-stroke 5 and gradually diminishes from that point to the top of the stroke. The pressure which has been established in the air vessel is that due to the maximum accelerating force exerted by the cylinder through the liquid upon 10 the piston, which occurs at the point of pick-up, and as the acceleration decreases the air re-expands and does work upon the piston by raising it relatively to the cylinder. Thus a portion of the work done in cushioning is rendered effective in raising the stamp; but the 15 quantity of the air and the degree to which it is compressed are not so great as to cause such an increase in the lift as to preclude the stamp falling by gravity alone the required number 20 of times per minute. Moreover, a comparatively slack piston without packing-rings can be employed without resulting losses, because the air vessel is always water-sealed, and should any water leak past the piston no further loss would be incurred than if it had 25 passed through the port.

To maintain sufficient liquid in the cylinders *a* notwithstanding leakage, liquid may be slowly and continuously circulated through 30 the reservoirs—for example, by means of a small pump (not shown)—the discharge side of which is connected to a supply vessel *p*, which may be formed in or as part of the entablature or frame in which the crank-shaft *g* 35 is mounted. The liquid flows thence into reservoir *h* of each cylinder through loosely-fitting telescopic tubes *q*, a passage *u*, and a channel *t*, that is connected with the lower portion of the reservoir *h*, through a passage *v*. 40 The liquid overflows from each reservoir *h* through a passage or port *x* into a passage *w* and thence through other telescopic tubes *r* into a discharge vessel *s*, formed in or as part of a lower member of the frame which 45 supports the guide-rods *c*. As each tube *q* communicates with the lower part of its respective reservoir *h* instead of with the upper part, the air displaced during each downward stroke from the air-space of the cylinder into that of 50 its reservoir (owing to the displacement of liquid by the piston-rod) cannot reach and escape through the supply-tube and carry liquid out with it, the flow of liquid into the reservoirs will be prevented from being disturbed, and the necessity for packing-glands 55 which would prevent the telescopic tubes moving freely is obviated. To minimize increase in pressure of the air in the air-spaces of the cylinder *a* and reservoir *h*, an air-escape hole 60 *z* establishes communication between the upper portion of the cylinder *a* and the overflow-channel *w*. Thus there is no air-cushion above the piston. The passage *t* is preferably cast in one with each cylinder. The passage *t* terminates below the normal level of the liquid

in the reservoir *h*. The upper part of this channel is in communication with the inlet-tube *q* through the passage *u*, and the lower portions of the channel *t* and reservoir *h* are connected by the passage *v*. *w* is another 70 channel, into which liquid overflows from the reservoir through a passage or port *x*, which which may be controlled by a valve *y*. The liquid passes from the channel *w* through the telescopic tube *r* to the vessel *s*.

l is a passage between the cylinder *a* and the channel *w*, through the external wall of which a soft-metal tube *2* is screwed, as shown in Fig. 4. The tube *2* is formed with an aperture *3*, and its inner end is formed with an 80 internal seat *4*, against which a plug *5* is screwed. Should an upwardly-moving cylinder meet a downwardly-moving head and an excessive pressure be thus caused in the cylinder *a*, the soft-metal tube *2* will be forced 85 out of its position and the pressure relieved. The plug *5* may be screwed back when it is desired to drain the cylinder, so as to enable the stamp to rest on the die without the motion of the cylinder being interfered with. 90 Instead of the tube *2* and plug *5* a safety-plug, consisting of a diaphragm held in position by a nut, may be employed, the nut being screwed into the wall of the cylinder and so arranged that an excessive increase of pressure ruptures the diaphragm, and thereby relieves the 95 pressure in the cylinder.

The axis of the shaft *g* is, as shown in Fig. 2, placed in such a vertical plane relatively to the vertical plane containing the axes of the several cylinders *a* that at the commencement of the lift or upward stroke of each stamp-head the rod connecting the cylinder thereof with the crank will be in a vertical or approximately vertical attitude. By this arrangement at the particular point at which the stamp-head commences to be lifted angular thrust on the guides *c* is practically eliminated and even during the remainder of the lifting stroke is less than would be the case 110 if the axis of the shaft *g* were in the vertical plane containing the axes of the cylinders *a*. 105

To enable the stamp-head to be held at the top of its stroke without stopping the motion of the cylinder, above the central guide *6* and 115 on one or both sides of each stamp-stem *7* I arrange a holder, which in one form, Figs. 7 and 8, comprises a metal block *8* of less width at the bottom than at the top, suitably supported in a frame *8^a* in proximity to the stem. 120

9 is an adjusting screw or key, whereby the block *8* can be forced toward the stem, so as to bring its upper edge into contact therewith, when upon the upward movement of the stem the block will be tilted and the stem be 125 free to move up, while on the stem moving downwardly the block will act after the manner of a toggle and jam the stem. The cylinder is of such a length that when the cylinder-head is in its lowermost position it will 130

be above the piston when the stamp-head is held up.

In order to compensate for the wearing away of the shoes and dies, each stem 7 is divided into two parts connected by an adjusting-sleeve 10, one end of which is provided with a tapered socket 11, which receives the end of one portion of the stem.

11^a is a keyway, through the upper part of 10 which a key can be inserted and passed through a slot in the stem end for the purpose of drawing the stem 7 into the tapered socket 11. A wedge inserted through the lower part of the keyway may be used for 15 forcing the stem out of the sleeve when desired. The other portion of the stem fits into the sleeve telescopically, and the stem is held firmly in the sleeve by a gib 12 and keys 13 in such wise that it can be quickly released to 20 admit of rapid adjustment. To prevent the adjustment becoming accidentally altered, the stem is formed at a suitable distance from its upper end with a collar 14, between which and the bottom of the sleeve 10 interlocking horseshoe-shaped washers 15 are inserted. These washers are in one arrangement formed with downwardly-extending end portions 16 25 and with recesses 17, so that by arranging them oppositely one above the other around the stem the portions 16 of one will engage with recessed portions of that below it and prevent accidental dislodgement, as a washer cannot be withdrawn until the sleeve has been raised. The collar 14 may also be formed 30 with recesses 17 to receive the portions 16 of the lowermost washer. Preferably the washers are about half an inch thick, so that by the disconnection of the parts of the stem and the insertion of each additional washer each half 35 an inch of wear of shoe and die is readily compensated for, not only as regards the relative position of the piston and the die-face, but also as regards the reduction in the total weight of the stamp caused by the wearing 40 away of the shoe.

For the purpose of keeping the stamp-heads slowly turning in one direction, so that the faces of the shoes and dies may be maintained approximately even, turning mechanism is arranged at a convenient distance from each stem 7 and the motion communicated thereto by a band, rope, or other flexible connector. In the arrangement illustrated (see particularly Figs. 12 and 13, which are 45 respectively a side elevation and a front elevational view of the turning-gear,) the adjustment-sleeve 10 is formed with a V-groove 18, adapted to receive an endless rope 19, which also passes around a grooved pulley 20, arranged in a plane at right angles thereto and provided with a ratchet-wheel 21. The pulley 20 is carried by one arm of a bell-crank lever 22, the other arm of which is suitably loaded for the purpose of maintaining tension 50 in the rope. This bell-crank lever is pivoted

upon a suspension-shaft 23, so as to be capable of turning freely thereon, and an arm 24, carrying a weighted pawl 25, engaging with the ratchet-wheel 21, is fixed to said shaft. During the fall of the stamp the lever 22 is 70 free to swing about the shaft 23, and the pulley 20 is free to turn about its own axis, and therefore there will be no tendency to turn the stamp-stem 7 about its axis; but on the lift of the stamp the pulley 20 is prevented from 75 turning about its axis by the pawl 25, and as the motion of the sleeve relatively to the pulley 20 tends to cause a difference in the lengths of the two sides of the rope a transfer of rope consequently takes place, the stamp-stem being turned thereby. As will be understood, the turning of the stamp-head may be obtained during the downstroke instead of the upstroke of the stamp-head, as may be desired, the turning mechanism being 80 arranged accordingly. In some cases the weighted pawl may be mounted direct on the suspension-shaft.

In carrying out my invention the details can be varied to suit circumstances and, as 90 will be evident, some of my improvements may be used without the others.

What I claim is—

1. Stamping apparatus comprising a gravity-stamp, lifting means for same, including a 95 cylinder, a liquid-cushioned piston and an air-chamber, closed except for free connection with the liquid cushion, as set forth.

2. Stamping apparatus comprising a gravity-stamp, lifting means for same, including a 100 cylinder, a liquid-cushioned piston and an air-chamber, in free connection with the liquid cushion, as set forth.

3. In stamping apparatus, the combination of a gravity-stamp, a positively-reciprocated 105 lifting-cylinder, a piston connected to the stamp-head and located in said cylinder, a liquid-containing chamber communicating with the cylinder-space beneath the piston and a closed air vessel which also communicates with the cylinder-space beneath said piston but not with the cylinder-space above it and is sealed by the liquid, as set forth.

4. In stamping apparatus, the combination of a gravity-stamp, a positively-reciprocated 115 cylinder, a piston connected to the stamp-head and located in said cylinder, a liquid-containing chamber, a port between said chamber and the cylinder-space beneath the piston, and an air vessel which communicates with said cylinder-space through another port at a lower 120 level than the first-mentioned port, as set forth.

5. In gravity stamping apparatus, the combination with the positively-reciprocated cylinder, of a liquid-containing chamber formed 125 around said cylinder and communicating with its lower part, a liquid-supply channel that communicates with the lower part of the liquid-reservoir, a discharge-channel that communicates with the upper part of the liquid- 130

containing chamber, and an air vessel communicating with the cylinder only below the communication between it and the liquid-containing chamber, as set forth.

5 6. In gravity stamping apparatus, the combination with the positively-reciprocated cylinder, of a liquid-containing chamber formed around said cylinder and communicating freely with the upper part thereof and with 10 the lower part thereof through a port, a liquid-supply channel that communicates with the lower part of the liquid-containing chamber, a discharge-channel that communicates with the upper part of the liquid-containing 15 chamber and an air vessel communicating with the cylinder only below the communication between it and the liquid-containing chamber, as set forth.

7. In gravity stamping apparatus of the 20 kind referred to, the combination of a positively-reciprocated cylinder, a piston connected to the stamp-head and located in said cylinder, a liquid-containing chamber communicating with the cylinder-space beneath said 25 piston, a discharge-passage communicating with the upper part of said chamber, a port between the lower parts of said cylinder and passage, a pressure-relieving soft-metal tube connecting said port with said passage and the 30 exterior of the apparatus and a drain-plug adapted to close communication through said soft-metal tube between said passage and the cylinder and the exterior of the apparatus, as and for the purpose specified.

35 8. In stamping apparatus, the combination of a stamp-stem formed in two parts, an adjusting-sleeve into which one part fits telescopically, means for fixing said part in the desired position in the sleeve and a tapered 40 socket formed in said sleeve into which the other part tightly fits as and for the purpose specified.

9. In stamping apparatus, the combination of a stamp-stem formed in two parts, an adjusting-sleeve into which one part fits telescopically, a gib and keys for fixing said part in the desired position in said sleeve and a tapered socket formed in said sleeve into which the other part tightly fits, as and for 45 the purpose specified.

10. In stamping apparatus, the combination of a stamp-stem in two parts, one of which is formed with a collar, a sleeve into which the part with the collar fits telescopically, means 50 for securing said part in the desired position

in the sleeve, washers arranged between the collar and sleeve and adapted to prevent the adjustment becoming accidentally altered and to compensate for the loss of weight of the stamp-head due to wear of its shoe, and means 60 for fixing the other part of said stem to said sleeve, as set forth.

11. In stamping apparatus the combination with an adjustable stamp-stem formed in two parts one of which is formed with a collar, a 65 sleeve into which the part with the collar fits telescopically, means for securing said part in the desired position in the sleeve, washers of horseshoe shape arranged between the collar and sleeve and having recesses and projections which are adapted to interlock, and means for fixing the other part to said sleeve, as and for the purposes specified.

12. In stamping apparatus, the combination with a stamp-stem of means for holding the 75 same in its raised position comprising a block of less width at the bottom than at the top, means for supporting said block adjacent to said stem but leaving it free to tilt, and means for moving said block so that its wide part 80 comes into contact with the stem and for holding said block in that position but allowing it to tilt, as set forth.

13. In stamping apparatus of the kind referred to, the combination of a stamp-stem, a 85 pulley whose axis is at an angle to that of the stem and which is free to turn in one direction only and a flexible part passing around said stem and pulley and adapted to impart to the pulley a turning movement when the 90 stem moves longitudinally in one direction and to impart a turning movement to the stem itself when it moves longitudinally in the other, as set forth.

14. In stamping apparatus, the combination 95 of a stamp-stem, a pulley whose axis is at right angles to said stem, an endless band encircling said stem and pulley, a ratchet-wheel connected to said pulley, a weighted bell-crank lever carrying said pulley and ratchet-wheel and a pawl adapted to engage said ratchet-wheel, as set forth.

Signed at West Hartlepool, in the county of Durham, England, this 29th day of May, 1900.

DONALD BARNS MORISON.
